UNITED STATES PATENT OFFICE.

CHARLES W. SPICER, OF BALTIMORE, MARYLAND.

DRIP CATCHER.

Application filed June 29, 1926. Serial No. 119,277.

The inconvenience incident to the dripping of oil and grease from the pans and transmissions of motor vehicles is well known. In many instances where such vehicles are kept in private garages on the owners' premises, the majority of such garages having a concrete or smooth hard floor, it is considered of great importance that the floor should be kept scrupulously clean, both on account of the appearance and in order that the owner, chauffeur or in some instances the repair man may inspect or work on the car from beneath without the inconvenience necessary to protect his clothes from oil and grease dropped on the floor.

The necessity for such protection in public garages and repair shops is even greater, as patrons object to the presence of grease on the floor on account of injury to tires and shoes, the danger of slipping and the tendency to track it into automobiles and residences. In repair shops it is very important to keep the floor clean on account of the necessity for getting under machines being repaired.

Various wide shallow drip pans have been used, but these are found undesirable and their use is limited because they are quickly destroyed when they are run over by the wheels of the machine, also to be completely effective they are necessarily of quite a large area and correspondingly heavy and difficult to empty.

The present invention relates to a drip catching device by which these various difficulties are overcome. It is of comparatively large area so as to catch the drip from all the various sources of oil, grease and gasoline in such a machine, and is at the same time so limited as to weight that it can be moved without difficulty and further it does not require emptying after the manner of the usual drip pan, as the element which catches the drip is newspaper or other waste paper which is gathered up to enclose the grease and burned or otherwise conveniently destroyed.

The device consists of a paper holding frame or clamp of sufficient area to underlie all the points from which oil and grease are apt to drip. This frame or clamp lies so flat on the floor that it is supported throughout against bending so that it is not injured when run over and in the interest of simplicity it is gravity closed dispensing

with the complications incident to springs and fastenings.

In the accompanying drawing I have illustrated a drip catching device embodying the features of my invention in the preferred form.

In the drawing:

Figure 1 is a plan of the frame enclosing a double sheet of newspaper ready for operation as a drip catcher.

Figure 2 is a side view of the same.

Figure 3 is an end view.

Figure 4 is a side elevation showing the lower portion of an automobile, the drip catcher being placed under the machine in the operative position. The dotted lines show the upper portion of the clamp raised to admit or release the papers.

Referring to the drawings by numerals, each of which is used to indicate the same or similar parts in the different figures, the apparatus as shown comprises a paper holder consisting of a plurality of elongated frames 1 and 2 of equal size and identical shape, as seen in the plan, so that the top frame 1 overlies and hides, in the plan view, the lower frame 2. These frame members or clamps 1 and 2 are connected together at one end or side by hinges 3-4, to swing about their ends one toward and from the other, and the frames are so constructed that they present each toward the other corresponding registering flat surfaces 6 and 7 on the upper and lower frames respectively, which when the clamping frames are closed, the upper frame being preferably held down by gravity, come in close contact. The upper frame being raised or swung upwardly a newspaper or other large sheet of paper is placed between the frames with the edges overlying the contacting surfaces 7 and clamped between the frames when the upper frame is lowered into position.

As the frames are of considerable size and, therefore, of appreciable weight the upper frame is conveniently held in position by gravity, no spring or fastening being necessary.

When the paper 10, three sheets being shown in Figure 2, is placed between the clamping members or frames, the contacting surfaces 6 and 7 of the frames engaging the entire edge portion around the complete circumference of the paper, the paper is held extended substantially in a flat horizontal

plane and may be moved and placed beneath the portion of the machine which drips grease and oil so that the floor requires protection in this way. The floor is thus protected against grease, the paper being held against displacement by wind or any other agency until it is desired to remove it to dispose of the accumulated grease when the paper is gathered together about the grease and burned, disposing of the paper and waste grease simultaneously.

The frames are most conveniently and cheaply made of flat strips 11 of sheet metal offset at the ends at 12 and riveted at the corner at 14. The strips may to advantage be identical as to all dimensions, being stamped out by means of a single die or jig, all parts being interchangeable.

An important advantage of the invention is, of course, the protection of the floor so that it will not accumulate grease which not only interferes with working on the machine from beneath, but is apt to be carried on the shoes of the passengers or operator of the vehicle into machine or residence where it injures and disfigures rugs, carpets, floors, etc. The invention described provides a cheap and convenient means for overcoming this difficulty.

I have thus described specifically and in detail a single embodiment of my invention in order that the nature and operation of the same may be clearly understood, however, the specific terms herein are used descriptively rather than in a limiting sense, the scope of the invention being defined in the claims.

What I claim and desire to secure by Letters Patent is:

1. A drip catching device for motor ve-

hicles consisting of a weight comprising a plurality of registering frames adapted to lie flat on the floor beneath the machine and to hold a sheet of paper extended to protect the floor, and a hinge connecting the frames at one side. 45

2. A drip catching device for motor vehicles to lie flat on the floor beneath the machine, the same comprising a sheet of paper and a weight to hold the paper in 50 horizontal position on the floor, the same consisting of plurality of registering frames between which the paper is gripped.

3. A drip catching device for motor vehicles to be placed in horizontal position 55 on the floor beneath the machine, the same comprising a sheet of paper and a weight to hold a sheet of paper and prevent displacement of the same, the weight consisting of plurality of registering frames between 60 which the paper is held, each of said frames consisting of flat metal strips secured together at the corners, the flat strips comprising the respective frames presenting mutually contacting surfaces substantially 65 throughout the periphery of the frames.

4. A drip catching device for motor vehicles comprising a weight to hold a sheet of newspaper, the same consisting of a plurality of cooperating registering frames connected together at one side to swing toward and from each other, the frames being adapted to lie flat on the floor in a horizontal plane, and the device being closed by gravity to clamp the sheet of paper between the 75 frames.

Signed by me at Baltimore, Maryland, this 28 day of June 1926.

CHARLES W. SPICER.
